Bertha S. Alsop
INVENTOR

UNITED STATES PATENT OFFICE

BERTHA S. ALSOPI, OF NEW YORK, N. Y.

BABY'S DIAPER

Application filed May 1, 1930. Serial No. 448,908.

My invention relates to babies' garments and particularly to a holder or support for diapers or pads.

One object of the invention is to provide a holder which is water-proof but which can be readily applied and securely held in place.

Another object is to provide a construction of this character which is comfortable to wear.

Another object is to provide a construction of the character described which can be readily cleaned and which is adapted to be easily applied.

In its preferred form the holder comprises outer and inner layers of water-proof silk or thin sheets of rubber. The inner sheet is provided with a large opening and a pocket is formed between the layers to receive the ordinary pad or diaper of absorbent cloth, paper or other material. The holder is shaped and provided with elastic portions so that when applied to a baby it is snug around the legs and around the waist without being uncomfortable or causing interference with the circulation of the blood or pressure on the sensitive nerve centers.

Fig. 1 is an outside view of the holder spread out flat.

Fig. 2 is an inside view.

Fig. 3 is a perspective view showing a garment with the parts in the position they would occupy when applied to a baby.

Fig. 4 is a detail view showing a modified form of connection.

The outer layer 7 is formed of a sheet of very thin rubber cloth or water-proof silk or the like considerably larger than the inner layer 8 which may be of similar material. The inner layer is provided with an opening 9 and the two layers are stitched or otherwise secured together at 10 around the edges, leaving a space between the layers to receive the absorbent pad 11. The upper and lower edges 12 and 13 are gathered in their central portion so as to provide waist band portions which are considerably elastic, particularly at the front and back of the body. The corners are provided with fastening devices such as 14, 15, 16 and 17 which are adapted to be secured together in the posi-

tion shown in Fig. 3. The sides are also gathered at 18 and 19 to provide elasticity around the legs.

When the garment is applied it will be seen that there is a very substantial fullness in the rear and lower portion to accommodate the pad 11 and permit freedom of movement of the child without loosening the portions of the garment which grip the legs and waist. Although the outer and inner layers may both be of the same material it should be understood that a layer of rubberized silk or the like might be used for the inner layer while a layer of rubber cloth is used for the outer layer or vice versa.

The inner layer, however, should preferably be smooth so as to provide a maximum degree of comfort to the child, whereas the outer layer is full and more elastic to accommodate itself to holding the pad in position. The outer layer may be made of more fancy material to conform in color or texture to the other garments of the child, if desired.

Loops or tabs such as 20 and 21 may be provided if desired for pinning or otherwise securing the garment to the child's waist or shirt and tab such as 22 may be provided if desired for supporting or holding up the stockings.

In the form shown in Fig. 4 one portion of the edge which constitutes the leg opening may be provided with a hook 25 to engage in one of the openings 26 in the outer portion so that the garment can be secured more tightly or more loosely around the leg or accommodate itself to the growth of the child.

In the form shown the garment may be more elastic in the center of the front and back and in the center of leg openings but it should be understood that all of each of the edges may be elastic. When desired the fastening straps 14 may be elastic and in that event the elasticity of the waist band portions 12 and 13 is not so important.

With this construction the pad is simply folded and inserted through the opening 9 in the inner layer into the space between the layers and it is unnecessary to fasten the pad to the holder or covering.

Constructions made as herein set forth

may have some of the advantages of my invention even though they are made of non water proof fabric for in such cases the inserted pad may have its own water proof outer sheath (not shown).

I claim:

1. A baby diaper holder garment of the character described having four edges and comprising outer and inner layers of water-
10 proof material secured together along their edges and having a pocket between them, the inner layer being substantially flat and having an opening therein for the insertion of a pad, the outer layer being gathered along
15 two opposite edges to provide elastic waist band portions and fastening devices at the opposite edges of said portions for detachably connecting the corners at one edge to the corners at the opposite edge to form an
20 elastic waist band.

2. A diaper holder comprising an elongated quadrilateral member consisting of outer and inner layers secured together along their outer edges, the inner layer being sub-
25 stantially flat and having an opening, and the outer layer being gathered along its edges and provided with substantial fullness in the center portion in line with said opening, and means for detachably connecting the corners at one edge to the corners at the opposite edge to form an elastic waist band and elastic leg gripping portions.

3. A baby diaper holder comprising two parts, a substantially flat inner layer of elastic material having four sides and having a central opening for the insertion of a flat absorbent pad the opening being of sufficient size to expose the major portion of the flat pad, and an outer member of resilient water-
35 proof material having its periphery secured to the inner layer on a line remote from the edges of the opening and being provided with substantial fullness in the center in line with the opening in the inner layer to form a shallow but extensive pocket for receiving and holding the edges of the flat pad and fastening devices at the four corners whereby two edges of the holder constitute an elastic waist band and the two other edges constitute elastic leg gripping portions.

4. A baby's diaper holder garment comprising a quadrilateral holder having water-
45 proof inner and outer layers secured together along their four edges, the inner layer having a central opening for the insertion of a pad, and the outer layer being gathered along its edges and fulled in the center, all the edges being elastic, and means for detachably securing the corners on the respective sides together to form an elastic waist band and elastic leg bands.

5. A child's garment comprising a normal-
55 ly flat diaper holder formed of two layers of waterproof fabric secured together along their peripheries, one layer being plain and

substantially flat, and having an opening in the center for the insertion of a pad, and the other layer being fulled opposite the opening, said holder having two opposite elastic edges provided with fastening devices and adapted to form an elastic waist band, and intervening elastic portions adapted to form elastic leg bands.

6. A child's garment comprising a diaper holder formed of two layers of waterproof elastic fabric secured together along their peripheries, the outer layer being plain and substantially flat and having an opening for the insertion of a pad, and the outer layer being fulled opposite the opening, said holder having two opposite edges provided with fastening devices and adapted to form an elastic waist band, and intervening portions adapted to form elastic leg bands, the leg bands having individual adjusting de-
60 vices.

7. A baby diaper holder comprising a sub-
stantially flat inner layer of elastic material having four sides and provided with a central opening for the insertion and removal of a flat absorbent pad, the opening being of sufficient size to expose the major portion of the flat absorbent pad, and an outer layer of resilient water-proof material having its peripheries secured to the inner layer, the area of the outer layer being materially greater than the opening so as to provide a substantial fullness in the center in line with the opening in the inner layer and to thereby form a substantially flat and shallow but extensive pocket for receiving the flat pad, said pocket being larger than the center opening and being overlapped by the margin of the inner layer surrounding the opening so that the flat absorbent pad is removably held with-
90 in the pocket by the overlapping marginal edges of the inner layer, and fastening devices at the four corners whereby two edges of the holder constitute an elastic waist band and the other two edges constitute elastic leg gripping portions.
